A. W. GRAHAM,
SPARK ARRESTER AND EXTINGUISHER.
APPLICATION FILED JAN. 27, 1909.

944,237.

Patented Dec. 21, 1909.

UNITED STATES PATENT OFFICE.

ANDREW WALTER GRAHAM, OF BRADFORD, PENNSYLVANIA.

SPARK ARRESTER AND EXTINGUISHER.

944,237.

Specification of Letters Patent. Patented Dec. 21, 1909.

Application filed January 27, 1908. Serial No. 474,441.

To all whom it may concern:

Be it known that I, ANDREW WALTER GRAHAM, citizen of the United States, residing at Bradford, in the county of McKean 5 and State of Pennsylvania, have invented certain new and useful Improvements in Spark Arresters and Extinguishers, of which the following is a specification.

This invention relates to spark arresters 10 and has special reference to a device for retarding the passage of cinders and sparks without obstructing the flow of the gas from the stack.

The principal object of this invention is 15 to provide an improved construction of spark arrester in which the sparks are caused to take a zigzag course in their passage through a stack.

A second object of the invention is to provide 20 a novel means of treating the sparks with steam during their passage.

With the above and other objects in view the invention consists in certain novel details of arrangement and combinations of 25 parts hereinafter fully described, illustrated in the accompanying drawings and specifically set forth in the claims.

In the accompanying drawings like characters of reference indicate like parts in the 30 several views, and; Figure 1 is a side elevation partly in section showing the front end of a locomotive equipped with this invention. Fig. 2 is an enlarged top plan view thereof. Fig. 3 is a detail perspective of a 35 portion of the stack lining. Fig. 4 is a detail perspective partly in section of the transverse plates and pipes. Fig. 5 is a vertical section through one of the pipes.

The numeral 10 indicates the front of a 40 locomotive provided with the stack 11. It is to be understood, however, that this device is adapted for use with other stacks than those on locomotives and the stack here shown is merely typical of any such device.

Within the stack 11 and lying against the 45 inner wall thereof is a plate 12 provided with a multiplicate of baffle plates or lugs 12 formed by punching out and striking up a portion of the metal. These baffle lugs 50 project inward and may be slightly inclined in either direction.

In order to allow the plate to be adjusted 55 to fit varying sizes of stacks it is provided on one edge with a plurality of slots 14 where through extend bolts 15 which serve

to hold the edges of the plate in adjusted position. Other bolts also serve to hold the plate 12 in proper position in the stack.

Centrally located in the stack are plates 17 each of which is provided with baffle lugs 18 struck up in the same manner as the lugs 13 but the lugs 18 project from both faces of each plate. The plates 17 are preferably arranged at right angles and are of such width that they may be fitted in any stack, being arranged with their edges in spaced relation to the wall of the stack and supported from the top thereof by means of brackets 19 held by the bolts 16. It is to be observed that the plates 17 may be positioned so that the lower ends thereof project below the base of the stack.

At 20 is indicated a main steam pipe connected to any suitable source of steam not deemed necessary here to be shown. At the upper end of this pipe is carried a head 21 with which is connected pipes 22 having closed ends 23 and being provided with a multiplicity of perforations 24 arranged throughout its length preferably in the form of upwardly inclined slits. These pipes are supported by brackets 25 bolted to the stack lining as at 26.

In the operation of the device as the exhaust gases carrying the sparks and cinders pass through the stack the jets of steam issuing from the perforations 24 strike the ascending sparks and drive them against one of the plates provided with baffle lugs. As the sparks strike these lugs they are thrown back but still move up slightly and strike against other baffle lugs when the operation is repeated. The spark thus moves along the stack at a very slow rate and in consequence is extinguished by the moist steam before it leaves the stack. Furthermore the beating of the sparks against the lugs pulverizes them and when they are ejected the upward motion will be so slow that they will fall in the immediate vicinity. In addition to this not only does the steam beat the sparks against the plates but it also creates an upward draft by reason of the upward inclination of the slits.

It is to be observed that there has thus been provided a simple and highly efficient device of the kind described and for the purpose specified as well as one which may be readily applied to any existing engine, it being merely necessary to lower the device

in the stack, secure it in place with the bolts and connect the pipe to an exhaust or steam pipe by the ordinary union.

Having thus described the invention, what is claimed as new is:

1. In a spark retarding device, the combination with a stack, of opposing surfaces arranged therein and provided with a multiplicity of baffle lugs, and a steam pipe, disposed between said surfaces, having a series of steam discharge openings, the lugs and steam jets being arranged to effect a constant to and fro movement of the sparks throughout approximately the full height of the stack.
- 10 2. In a spark retarding device, a stack, a

lining therefor having a multiplicity of upwardly and inwardly inclined baffle lugs, diametrically disposed plates having their edges spaced from the lining and provided with upwardly inclined baffle lugs and steam pipes provided with a multiplicity of upwardly inclined slits held in the angles formed by said plates and in spaced relation thereto.

20 25 In testimony whereof I affix my signature, in presence of two witnesses.

ANDREW WALTER GRAHAM.

Witnesses:

MAY M. PLYER,
ALBERT POPKINS.
